TAPE PROCESSING MACHINE

Edward H. Brown, Grand Rapids, Mich., assignor
to McInerney Spring & Wire Company, Grand
Rapids, Mich., a corporation of Michigan

Application October 28, 1943, Serial No. 508,074

8 Claims. (Cl. 91—14)

This invention relates to a tape processing machine and is directed to the rapid production of short lengths of tape which are trapezoidal in form and at each end at each side thereof is supplied with a narrow band of adhesive. The short lengths of tape at one side are longer than at the other with the end edges located at acute angles to the longer side and the adhesive side is applied to each side of the tape at each end in a narrow strip substantially parallel to the end edges. The present invention has for its primary object and purpose a rapid quantity production of the relatively short lengths of tape with the adhesive thereon as described.

An understanding of the invention and of a preferred construction of machine embodying the invention may be had from the following description, taken in connection with the accompanying drawings, in which,

Fig. 1 is a side elevation of a tape processing machine built in accordance with my invention.

Fig. 2 is an end elevation thereof.

Fig. 3 is a fragmentary enlarged vertical section through the adhesive applying portion of the machine.

Fig. 4 is a plan view thereof.

Fig. 5 is a fragmentary side elevation of the tape severing means.

Fig. 6 is an edge view thereof, and

Fig. 7 is an illustration of one of the short lengths of processed tape after completion of the processing thereof.

Like reference characters refer to like parts in the different figures of the drawings.

In the construction of the machine a frame is provided including two spaced relatively long vertical posts 1 connected at their upper ends by a cross bar 2. Other vertical posts 3 of less height are utilized, spaced from the posts 1. Horizontal frame bars 4 connect the upper end of the posts 3 with the posts 1 and between said bars 4 horizontal bar supports 5 are provided.

A short distance inward from the upper ends of the posts 3 other vertical posts 6 are secured at their lower ends to the bars 4 and are connected at their upper ends with the posts 1 by horizontal bars 7 located over the bars 4. Approximately midway between the ends of the bars 7 relatively short vertical posts 8 are secured thereto at their lower ends. Horizontal bars 9 are pivotally mounted at one end, at 10, to the upper ends of the posts 8 and extend over the bar 2, being connected at their free ends by a cross bar 11 which lies directly over the bar 2

and is adjustably mounted with respect thereto by a threaded bolt 12 with nuts thereon which may be adjusted to different positions so as to adjust the bars 9 about the axis of the pin 10.

At the outer sides of the post 3 supporting hooks 13 are secured for carrying a roll of tape 14. The tape unwinding from said roll is carried through an adhesive holding container 15 mounted on and lying between the posts 4, at the under side of which a heating element 16 may be secured, which in practice is an electric coil construction of conventional form. A vertical guide 17 (Fig. 3) for the tape extends upwardly above and through the bottom of the adhesive container, one side thereof being extended downwardly and curved as at 18 for a change of direction of the tape to pass through the vertical guide 17. The container 15 contains a quantity of liquid adhesive 19 maintained at the desired temperature by the heating element 16.

Two rollers 20 are mounted on horizontal shafts 21 over and extend partly within the adhesive at 19. The rollers are equipped at equally spaced distances around the peripheries thereof with wicks 22 of felt or other equivalent adhesive absorbing and carrying material. Said wicks are located diagonally across the peripheral faces of the rollers 20 and alternately are reversed in angular position. The wicks are located so that complementary wicks on the two rollers come together on rotation of the rollers in opposite directions. The tape 14 carried vertically through guide 17 is pressed by the wicks at opposite sides of the tape at equally spaced distances in the tape length but with the wicks located diagonally across the tape at both sides and with any two successive applications of adhesive disposed in angular relation to each other. The shafts 21 which carry the wick holding rollers 20 are mounted on suitable bearings 23 carried by the bars 4 of the frame.

The tape 14 is moved upwardly over a roller 24 which is mounted for adjustment in a support 25, the ends of the roller shaft being located in horizontal slots in the support and engaged at opposite sides by the ends of adjusting screws 26. This permits a proper adjustment or shifting of the roller 24 whereby the tape is held in its proper vertical position to move through the guide 17 without rubbing against the sides thereof and to be properly centered between the two complementary wicks 22 which press against the opposite sides thereof and transfer the adhesive to the tape where it is engaged by the wicks.

The tape 14 passing over the roller 24 is directed horizontally to the severing means. Such severing means consists of a lower flanged roller 27 carried on a shaft 28 which is mounted at its ends in suitable bearings supported on the horizontal bar 1. At equally spaced distances around the roller 27 blocks 29 are secured and held, the outer sides of the blocks being substantially flush with the periphery of the roller. These blocks are located diagonally or at an angle with respect to the plane of the roller and the alternate blocks are disposed at angles to each other, the same as the wicks 22. Over the roller 27 a second flanged roller 30 is located and mounted upon a shaft 31 which is carried by bearings fixed to the upper adjustable bars 9 of the frame. The roller 30 has secured thereto around its peripheral portions a plurality of tape cutters 32 equal in number to the blocks 29 and having cutting projections which extend slightly beyond the periphery of the roller 30 and which when such cutter projections come to the blocks 29 thereto act to cut the tape located between said block and cutter. The peripheral faces of the rollers 27 and 30 bear against each other and operate to grip the tape inserted between them and draw it continuously from the roll of tape mounted upon the brackets at 13. The rollers 27 and 30 therefore act as feed rollers for the tape in addition to their function served in cutting the tape diagonally across. The exterior radius of the faces of the rollers 27 and 30 is the same as the radius extending from the center of the shaft 24 to the outer face of a wick 22.

The mechanism is driven preferably by an electric motor 33 carried on the lower bars 4 and the bars 5 of the frame and which through a speed reducer, the housing of which is indicated at 34, drives a shaft 35 at relatively low speed. On the shaft 35 a sprocket wheel 36 is secured. A driving chain 37 passes around the sprocket wheel 36 and around wheels on the shafts 21, 28 and 31 as shown in Fig. 1, driving the two shafts 21 in opposite directions and likewise the shafts 28 and 31 in opposite directions. With the machine described the continuous tape indicated at 14 is processed to cut it into short tape lengths shown at 38 in Fig. 7 which are of a trapezoidal form, that is, with one side longer than the other and with the ends diverging from each other from the shorter to the longer side. The cutting of the tape by the knives at 32 is midway between the side edges of the adhesive strips or bands which are applied to the tape at spaced apart intervals. Therefore each final tape at 38 at each end is supplied with a narrow band of adhesive 39 at both sides thereof, the bands being parallel to the end edges of the tape as shown.

When the short lengths of tape are successively cut from the continuous length 14 they are carried and delivered to an inclined chute 40 (Fig. 1) down which they slide to a receptacle to receive them.

The construction described is of a practical and useful character and has been built and is in continuous successful use.

The tape sections 38 are used, several of them, in the construction of a parachute, being wrapped around the shroud lines which extend over the fabric of the chute and downwardly below it, such wrapping being where the lines pass across the edges of the fabric. The tape as processed in the present invention is likewise of fabric and in the construction of a large quantity of

parachutes a much larger quantity of the sections of tape with adhesive applied at each end of its ends is required. The present machine produces them very rapidly and in large quantity and in uniformity and identity with each other.

The invention is defined in the appended claims and is to be considered comprehensive of all forms of structure coming within their scope.

10 I claim:

1. In apparatus of the character described, means for moving a length of tape continuously in the direction of its length, means for applying adhesive to the tape at opposite sides thereof at spaced intervals in the length of the tape, and means for severing the tape at the places where the adhesive has been applied and substantially midway between the side edges of said adhesive applications.

20 2. In apparatus of the class described, means for continuously moving a length of tape in the direction of its length, means for applying adhesive transversely of the tape at opposite sides thereof and at an angle to the length thereof at spaced intervals in the length of the tape and for applying said adhesive at alternate applications thereof, at reversed substantially like angles to the length of the tape, and means for severing the tape at said applications of adhesive thereto substantially midway between the side edges thereof.

30 3. In a construction of the class described, driven rollers between which tape may be continuously drawn in the direction of its length, cooperating severing means carried by said rollers for cutting the tape transversely at spaced distances in the length of the tape, and means between which the tape is drawn for applying adhesive to opposite sides of the tape at the places where said transverse severings take place and to a short distance at each side thereof.

40 4. A construction containing the elements in combination defined in claim 3, said means for applying the adhesive comprising spaced rollers, adhesive carrying members carried on said rollers and adapted to be brought together simultaneously at opposite sides of the tape, and means for continuously driving said rollers and for driving said tape drawing and severing rollers.

50 5. In apparatus of the character described, means for supporting a roll of tape on a horizontal axis, spaced rollers for engaging said tape for continuously drawing it in the direction of its length from said roll, cooperating transverse cutting means carried by said rollers for cutting the tape transversely at spaced distances in the length thereof, two rotatable adhesive applying rollers mounted to turn on horizontal axes, spaced wicks adapted to absorb and carry adhesive extending from said rollers, a receptacle for liquid adhesive into which said rollers extend, means for vertically guiding the tape as it is moved through said receptacle without contacting the adhesive and between the rollers for the application of adhesive to the tape at spaced distances in the length thereof, the adhesive wicks on said rollers coming against substantially equal areas on opposite sides of said tape simultaneously and means for continuously driving said tape moving and severing rollers and said adhesive applying rollers.

60 6. A construction containing the elements in combination defined in claim 5, said means for driving said rollers comprising a continuously

operating prime mover, a shaft driven thereby, a chain driving wheel on said shaft, and an endless chain engaging said wheel, said tape moving and severing rollers and said adhesive applying rollers having like wheels driven by the chain.

7. In a construction of the class described, means for drawing a continuous length of tape in the direction of its length, spaced rollers mounted to turn about horizontal axes, adhesive carrying wicks mounted at spaced distances around the rollers and projecting outwardly from the peripheries thereof, means for driving said rollers in opposite directions with the outer ends of the wicks moving at substantially the same lineal speed as the longitudinal movement of said tape, whereby the wicks are simultaneously brought against opposite sides of the tape at spaced distances in the length thereof, a container for liquid adhesive into which the lower portions of the rollers extend, a vertical guide extending through said liquid container

through which the tape passes, and means for cutting the tape transversely at the places of adhesive application thereto and between the opposite sides of the adhesive applications.

- 5 8. In apparatus of the character described, a support, two spaced rollers mounted to turn about horizontal axes on said support, adhesive carrying wicks mounted at spaced distances around said rollers and extending beyond the peripheries thereof, means for drawing a continuous length of tape between said rollers at a predetermined speed, means for driving the rollers at speed such that the outer ends of said wicks have substantially the same lineal speed as the tape movement, means for supplying adhesive to said wicks for transference thereof to the tape upon engagement of the wicks against the opposite sides thereof and means for cutting the tape transversely at the places of adhesive application thereto and between the side edges of said adhesive applications.
